CLAIM

The ornamental design for a decorative light, as shown and described.

DESCRIPTION

FIG. 1 is a first perspective view of a decorative light;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion "9" in FIG. 1;

FIG. 10 is an enlarged view of the selected portion "10" in FIG. 1;

FIG. 11 is an enlarged view of the selected portion "11" in FIG. 1; and,

FIG. 12 is an enlarged view of the selected portion "12" in FIG. 2.

Any shading and cross-hatching are not features of the design but are utilized to illustrate the surface contours of the decorative light design in the drawings.
